UNITED STATES PATENT OFFICE

HAERY B. HULL, OF DAYTON, OHIO, ASSIGNOR, BY MESNE ASSIGNMENTS, TO
FRIGIDAIRE CORPORATION, A CORPORATION OF DELAWARE

REFRIGERATING APPARATUS

Application filed February 25, 1926. Serial No. 90,670.

This invention relates to refrigerating apparatus and particularly to the condensing and receiving units for such apparatus.

One object of this invention is to provide a receiver in which the danger of leakage of liquid refrigerant is reduced to a minimum.

Another object is to provide a simple receiver which may be readily manufactured and assembled.

10 A further object is to provide a receiver which presents a relatively large surface to the atmosphere.

Another object is to provide a combination of a condenser and a receiver which occupies a relatively small space.

Further objects and advantages of the present invention will be apparent from the following description, reference being had to the accompanying drawings, wherein preferred embodiments of the present invention are clearly shown.

In the drawings:

Fig. 1 is a diagrammatic elevation of a refrigerator system embodying the invention.

25 Fig. 2 is a diagrammatic elevation looking in the direction of the arrow in Fig. 1, showing a modified form of condenser and receiver coils and the motor driven fan.

Fig. 3 is a sectional view on the line 3—3
30 of Fig. 2.

The compressor 10 is driven by a motor 11 through pulleys 12 and 13 and belt 14. The compressed refrigerant is forced through pipe 15 to the condenser coil 16 where it becomes liquid, and then drops to receiver coil 17. From the receiver coil liquid refrigerant is forced through a pipe 18 and a cooling unit 19.

40 Cooling unit 19 may be of any form desired. The refrigerant in the cooling unit 19 expands when heat is absorbed. The expanded gas is withdrawn from the unit 19 through a pipe 20 by the compressor.

45 In Fig. 1 there is shown an improved form of condenser and receiver adapted to be used in a system such as is described above. The condenser coil is composed of a plurality of turns 16 of round copper tubing of small diameter. These turns are spaced apart so that

there is ample room for the circulation of air through them.

Connected in series with and directly below the condenser coil is the receiver coil 17. This coil is also made of copper or any other suitable metal tubing which is of considerably larger diameter than the tubing of the condenser coil and its turns are placed substantially in contact with each other. The two coils may be connected in any suitable manner as by inserting the smaller tube within the larger tube and soldering the two together.

55 The motor 11 which drives the compressor carries at one end of its shaft a fan 21. This fan is adapted to cause the circulation of air around the condenser and receiver coils.

In the modification shown in Figs. 2 and 3, the combined condenser and receiver unit 22 is made of a single integral piece of tubing 60 of relatively large diameter. The upper turns 24 of this coil are flattened to reduce their cross section, while the lower turns retain their round shape. The flattened portion of this coil presents a relatively large cooling 65 surface to the compressed refrigerant which passes therethrough so that the condensing of this refrigerant takes place more rapidly than would be the case in a round coil having the same exposed surface, that is, the 70 volume of gas in the flattened coil is less than the volume that would be contained in a round coil having the same surface area.

In assembling this unit the flattened turns which act as a condenser are spaced from 75 each other while the round turns 23 which act as a receiver are substantially in contact with each other.

80 It is readily apparent that by making the condenser coil of relatively small tubing in one case or flattened as in the other case, a large amount of this coil may be wound in a small space. Likewise by placing the turns of the receiver substantially in contact with each other, a large amount of this coil is utilized, thus the assembled unit in this invention occupies no more space than is required where the condenser coil alone is used in the conventional structure.

85 By making the receiver in the form of a 100

coil of tubing of large diameter a relatively large surface is exposed to the air as compared with the present form of receiver, so that any refrigerant which may not have been liquefied in the condenser proper will be reduced to a liquid state in the receiver.

The present receiver which is simple in construction is cheaply and easily assembled and reduces to a minimum the danger of leakage, which is present in the conventional cylindrical or rectangular receivers now in use.

While the forms of embodiment of the present invention as herein disclosed, constitute preferred forms, it is to be understood that other forms might be adopted, all coming within the scope of the claims which follow.

What is claimed is as follows:

- 20 1. In a refrigerating apparatus, a condenser comprising a coil of tubing of relatively small cross section, and a receiver for liquid refrigerant connected in series with the condenser comprising a coil of tubing of relatively large cross section.
- 25 2. Apparatus as defined in claim 1 in which the turns of the condenser coil are spaced apart and the turns of the receiver coil are substantially in contact with each other.
- 30 3. In a refrigerating system, a condenser coil and a receiver coil connected in series with said condenser coil, the turns of said condenser coil being spaced apart, and the turns of said receiver coil being substantially in contact with each other.
- 35 4. In a refrigerating system, a condenser coil, a receiver coil, and a fan for effecting the circulation of air around said condenser coil and said receiver coil.
- 40 5. In a refrigerating system a unitary condenser and receiver structure comprising a single integral piece of tubing wound into a coil, the tubing in some of the turns of said coil having a smaller cross section than that in other of the turns.
- 45 6. In a refrigerating system a unitary condenser and receiver structure comprising a single integral piece of tubing wound into a coil, the tubing in some of the turns of said coil having a greater surface per unit volume than that in other of the turns.
- 50 7. In a refrigerating system a unitary condenser and receiver structure comprising a single integral piece of tubing wound into a coil, the tubing in some of the turns of said coil being flattened to provide a condenser conduit of relatively small cross section, and the tubing in other of the turns having a relatively large cross section.
- 55 8. In a refrigerating system a unitary condenser and receiver structure comprising a single integral piece of tubing, one portion of said tubing having a substantially constant cross section, and another portion of said tubing having different substantially con-

stant cross section, said tubing being wound into a coil.

9. In a refrigerating system a unitary condenser and receiver structure comprising a single integral piece of tubing, a portion of the tubing having a substantially constant surface per unit volume, and another portion of said tubing having a different and substantially constant surface per unit volume, said tubing being wound into a coil.

10. In a refrigerating system a unitary condenser and receiver structure comprising a single integral piece of tubing wound into a coil having an upright axis, the upper turns of the coil having a relatively small cross section and the lower turns of the coil having a relatively large cross section.

11. In a refrigerating system a unitary condenser and receiver structure comprising a single integral piece of tubing wound into a coil having an upright axis, the tubing in the upper turns of the coil having a relatively large surface per unit volume and the tubing in the lower turns of the coil having a relatively small surface per unit volume.

In testimony whereof I hereto affix my signature.

HARRY B. HULL.
